UNITED STATES PATENT OFFICE.

JOHN FREDERICK BENNET, OF LONDON, ENGLAND.

CALENDAR.

Application filed March 25, 1927, Serial No. 178,411, and in Great Britain March 29, 1926.

This invention relates to calendars of the type comprising a strip of transparent material located over the date pad, cards or the like in a vertical or horizontal manner with an adjustable date indicator slidably mounted thereon and having one or both ends furnished with carrying slides adapted to engage with the date pad or cards or with guide bars or strips formed with or attached to the carrier for the date pad or cards.

In calendars of the above type as previously constructed the slides have been secured to the ends of the transparent strip by means of staples, by eyelets, or by bending round the end of the strip, forming it with apertures, and providing the slide with projections for entering these apertures.

According to the present invention the slides are formed or provided with pointed portions in suitable positions which are adapted to pierce the material of the transparent strip to hold the slide attached thereto.

The slides may be of hook-like form as already known in such devices to engage over a date pad, guide bar or the like and in some cases may have bent lugs or other means, of a known kind, for engaging under the lower edge of a guide bar or the like.

In order that the invention may be better understood it will now be described with reference to the accompanying drawings in which:—

Fig. 1 is a perspective view of one form of calendar made according to the invention.

Fig. 2 is an enlarged perspective view of the transparent strip and slide as used in the calendar shewn in Fig. 1.

Fig. 3 is a sectional elevation of the upper portion of the strip and slide shewn in Fig. 2.

Fig. 4 is a similar view to Fig. 3 but of a further form of the invention.

Figs. 5, 6, 7, 8 and 9 shew perspective views of other modifications.

In Figs. 1 to 3 which shew one particular form of calendar constructed according to the invention which comprises a strip 10 of transparent material such as celluloid having one end bent back on itself, the short arm 11 coming at the back. The slide is formed from sheet metal, for instance of brass of light gauge and is of the same width as the strip. Before bending into form, the slide is of rectangular shape the short side of the rectangle being the width of the transparent strip and the longer side about twice the length of the short side.

One end of the strip is bent up at 12 and doubled back on itself, the bent up part being about a fifth of the total length of the strip. This bent up part has two or more points 13 struck up therefrom and these points are directed towards the back portion 14 of the strip, which opposite the points is formed with depressions 15.

The lower end of the short arm 11 of the transparent strip 10 is passed between the bent up part 12 of the metal strip and its back part 14 and suitable pressure applied to the parts. This causes the points 13 to penetrate this part 11 of the transparent strip and by continued pressure or light blows, the points 13 which enter the depressions 15 contact with the bottoms thereof and are bent outwards. The slide is thus firmly secured to the transparent strip.

The other end 16 of the rectangular metal strip to form the slide is bent downwards so that it is adapted to come over the bend of the transparent strip, the upper portion of the slide at the front having a groove formed thereon to leave the upper end shaped as a somewhat cylindrical finger or handle piece 17.

In use the slide carrying the transparent strip 10 is engaged over a date pad so that the strip lies on the pad and is vertical whilst the other rear parts of the slide and strip 14 and 11 respectively come at the back of the pad at the top. On the strip is located the adjustable indicator 18 which is frictionally retained in position and the lower end of the strip 10 may if desired be bent up at 19 as shewn to come at the back of the date pad or may be furnished with means to prevent the accidental removal of the indicator.

If desired both ends of the transparent strip may be furnished with a slide such as described and in this case the transparent strip may be arranged horizontally the slides having sufficient grip to hold the device in position on the date pad or the like.

Where the slides are to engage around and under a guide or bar such as 20 (Fig. 1), the turned up part 12 which is attached to the downturned end 11 of the transparent strip 10 may not extend the full width of the slide but only occupy the central portion leaving two side tongues 21 one on each side which are adapted to come under the bar or strip 20 to maintain the device in position thereon.

In place of bending over the end or ends of the transparent strip 10 to engage the slide

these ends may not be bent over but may as shewn in one constructional form in Fig. 4 come between doubled thicknesses 22 and 23 at the front of the slides one thickness having 5 the points or the like 13 for perforating the transparent strip 10 and the other if desired having depressions 15, apertures or the like co-operating with the points if desired.

According to another constructional form 10 of the invention the transparent strip is utilized without a slide or slides. In this form as shewn in Fig. 5 both ends of the slide are doubled or hooked over at 24 so that one edge engages around one edge of the date 15 pad or the like and the other edge around the parallel edge of the pad.

With a similar construction but with one or both ends bent or hooked as shewn for example in Fig. 6 the bent end or one of the 20 bend ends or both, have a portion 25 of the material of the transparent strip 10 struck up just before the bend so that a tongue is formed which constitutes a manipulating handle.

25 To increase the grip of the device on the date pad or the like in this last mentioned form a thin sheet metal slide such as 26 (Fig. 7) may be provided consisting of a short doubled strip with a struck up tongue 30 27. This strip 26 comes on each side of the date pad or the like so that the portions thereof grip the pad and the hooked over end of the transparent strip is hooked over the slide so that the tongue 27 of the slide passes 35 through the aperture left in the strip 10 and comes adjacent the tongue 25 of the transparent strip.

As a further modification of this form and

to adapt it to slide on a bar or strip the rear thickness of the slide 26 is formed on its 40 lower edge with lugs or the like 28 shewn dotted in Figs. 7 and 8 adapted to come below the lower edge of the bar or strip and thus retain the device in position.

Fig. 9 shews a form of the invention where 45 an endless band or strip 29 of transparent material entirely encircles the date pad 30. With this construction the transparent material to form the strip can be made of lighter gauge than with previous constructions. The 50 joint in the material preferably comes on the back of the date pad, the indicator 18 sliding in frictional engagement with the front.

The invention is not limited to the forms 55 of calendars described or to the precise constructional details as these may be varied to suit particular cases.

What I claim as my invention and desire 60 to secure by Letters Patent of the United States of America is:—

1. In a calendar of the class described, a transparent strip and a slide to carry the strip, said slide having prongs integral therewith, extending through the material of the strip and securing the latter to the slide.

65 2. A calendar as claimed in claim 1, in which the slide is hook shaped to engage over a suitable portion of a calendar pad.

3. A calendar as claimed in claim 1, in which the slide is of hooked shape to engage over a portion of a calendar pad and in which the rear edge of the slide is provided with 70 lugs for engaging the calendar.

In witness whereof I affix my signature.

JOHN FREDERICK BENNET.
